UNITED STATES PATENT OFFICE.

ALBERT PETER, OF KINGSTON, MICHIGAN.

DOOR-LOCKING APPARATUS.

1,287,740.

Specification of Letters Patent. Patented Dec. 17, 1918.

Application filed September 21, 1918. Serial No. 255,105.

To all whom it may concern:

Be it known that I, ALBERT PETER, a citizen of the United States, residing at Kingston, in the county of Tuscola and State of Michigan, have invented certain new and useful Improvements in Door-Locking Apparatus, of which the following is a specification, reference being had therein to the accompanying drawings.

10 This invention relates to a door locking apparatus, and has for its object the construction of a comparatively simple and efficient mechanism for simultaneously locking a plurality of doors, by the operator manipulating a single control grip or handle.

With this and other objects in view, the invention comprises certain peculiar combinations and arrangements of parts as are clearly illustrated in the accompanying drawings, 20 specifically described in the following specification and more particularly pointed out in the appended claims.

In the drawings,

Figure 1 is a view in front elevation of a 25 cabinet or structure equipped with my locking apparatus, while

Fig. 2 is a vertical, sectional view taken on line 2—2 of Fig. 1.

Fig. 3 is a horizontal, sectional view taken 30 on line 3—3 of Fig. 2.

Fig. 4 is a fragmentary, perspective view of the apparatus.

Fig. 5 is an enlarged, vertical sectional view of the apparatus.

35 Fig. 6 is a view in side elevation of the manipulating handle or control and the cooperating parts associated therewith, the parts shown in this figure being removed from the frame or cabinet.

40 Referring to the drawings by numerals, 1 designates the cabinet or frame which is provided with preferably a plurality of pairs of hinged doors 2, 2; each door is provided with the usual knob or grip 3.

45 Secured across the cabinet 1, and extending across the inner face of each door 2, is a supporting bracket or cleat 4; this bracket 4, in each instance, is preferably placed near the upper end of the upper doors and near

50 the lower ends of the lower doors, although there is no particular novelty in the location of the brackets 4, whether near the upper or the lower edges of the doors; the object is to place these brackets 4 out of the way so that

55 when the doors 2 are open the brackets will not interfere with the storing of articles or

goods in the compartment or spaces behind the door or doors.

Arranged transversely of the brackets 4 are auxiliary brackets 5 (Fig. 3); and in these brackets 5 are rotatably mounted shafts 6, preferably square in cross section, and to these shafts are connected substantially U-shaped hook devices 7. Each hook device 7 comprises a body, of substantially U-shape, 65 as stated, terminating at its ends in eyes 8, which surround shaft 6. The hook device 7 is fixedly secured to the shaft by reason of the bore of each eye being square and fitting snugly over the shaft 6 so that when a rotary movement is imparted to shaft 6, the hook devices 7 will be moved for either locking or 70 unlocking the doors 2, as hereinafter described.

On each door 2 is a catch 9, of any ordinary type, which will ride over the hook device 7, and when the devices 7 are raised, as shown in Fig. 5, the hooks 9 will securely retain the doors in a closed, locked position, but when the square shafts 6 are 80 rotated so as to swing the hook devices 7 downwardly, as shown in dotted lines in Fig. 5, the catches 9 will be released, and by the operator grasping the knobs 3, the doors 85 can be opened.

A central strip 10 carries a rotatably mounted disk 11, and to this disk 11 is secured a grip or angle plate 12, and pivotally mounted at 13, upon the disk 11, are the inner ends of links 14, the outer ends of the 90 links being pivotally connected at 15, to arms 16, that have eyes 17 formed upon their outer ends, which eyes 17 have square bores that fit snugly over the square shafts 6, Fig. 6. When the grip 12 is closed against the strip 95 10, Fig. 2, the hook devices 7 will be in a raised position, Fig. 5, and as each door is closed the catch 9, carried thereby, will ride over the hook device and will secure the door closed until the operator swings the grip 12 100 upwardly to the position shown by dotted lines in Fig. 5, whereupon the catches 9 will be released, by reason of the hook devices being then in their lowest position, shown by dotted lines.

105 The grip 12 is provided with an elongated aperture 18, that permits the staple 19 to pass therethrough, and by employing an ordinary padlock the doors can be securely fastened against fraudulent opening.

110 It will be understood from the foregoing that I produce a simple and efficient appa-

ratus whereby a number of doors or gates can be locked by a single operator, and such is desirable in storehouses, or in refrigerator plants, or by covering the catches so that a 5 criminal cannot tamper with the same my device may be readily adaptable to a prison or jail.

What I claim is:

1. In an apparatus of the class described, 10 the combination with a frame provided with a bracket, a door carried by said frame, of a disk rotatably mounted upon said frame, a grip attached to said disk, a shaft rotatably mounted upon said bracket, a hook device 15 carried by said shaft, a catch carried by said door and co-operating with said hook device for locking the door in a closed position upon said frame, and means pivotally connecting said shaft to said disk whereby 20 movement imparted to the disk through the grip will place the hook device in a locked or unlocked position with respect to said catch.
2. In an apparatus of the class described, 25 the combination of a frame provided with a plurality of sets of doors, brackets secured transversely across said frame and being positioned contiguous to the ends of the doors, said frame provided at its center with 30 a rotatable disk, an angle grip provided with an elongated aperture secured to said disk, auxiliary brackets secured upon said first-mentioned brackets, shafts square in cross section, journaled in said auxiliary brackets, 35 hook devices provided with eyes, said eyes having square bores and fitting over said shafts, catches on said doors adapted to engage said hook devices for retaining the doors in a closed position, arms provided at

their outer ends with eyes fitting over the 40 square shafts, and links pivotally connected at their outer ends to said arms and pivotally connected at their inner ends to said disk.

3. In an apparatus of the class described, 45 the combination with a frame, a door carried by said frame, of a rotatable disk provided with an apertured grip, a pair of transversely-positioned auxiliary brackets supported upon said frame, a shaft rotatably mounted in said auxiliary brackets, a U- 50 shaped hook device having its ends surrounding said shaft, a catch carried by the inner face of the door and adapted to engage said hook device for locking the door in a closed position, an arm provided with an eye 55 surrounding said shaft, and a link pivotally connected at one end to said disk and pivotally connected at its opposite end to said arm.

4. In an apparatus of the class described, 60 the combination with a frame, of a plurality of pairs of doors upon said frame in the same horizontal plane, a single shaft carried by said frame contiguous to all of said doors, a pair of U-shaped hook devices 65 fixedly secured to said shaft behind the doors, said U-shaped hook devices extending from said shaft toward said doors, a pair of catches secured to each pair of doors and each pair of catches engaging a single hook 70 device, and a manually-controlled operating device secured upon the middle of said frame, between the pairs of doors, and being connected to the shaft for moving the shaft to locked or unlocked positions.

In testimony whereof I hereunto affix my signature.

ALBERT PETER.
